UNITED STATES PATENT OFFICE.

JACOB WHEATFIELD, OF BALTIMORE, MARYLAND.

DESIGN FOR A BLANK FOR GARMENT-FASTENING HOOKS.

SPECIFICATION forming part of Design No. 28,978, dated July 5, 1898.

Application filed June 4, 1898. Serial No. 682,609. Term of patent 3½ years.

To all whom it may concern:

Be it known that I, JACOB WHEATFIELD, a citizen of the United States, residing in the city of Baltimore, in the State of Maryland, 5 have invented and produced a new and original Design for a Blank for a Garment-Fastening Hook, of which the following is a specification, reference being had to the accompanying drawing, forming a part thereof, which 10 shows the blank in plan view.

My design for a blank for garment-fastening hooks consists of the two sections A and B, divided by a straight bar C. The section A has upwardly-extending side arms a, the 15 outer marginal lines of which form a continuous curve forming an upper arched end a'. Extending outwardly from median line of the device on each side is a protruding curved ear c, having inverted curves c' at upper and lower 20 part thereof. Within each of the ears c is a quadrangular aperture c''. Above the upper margin of the bar C the section A has an opening A', the lower end of which is in a right line from which said opening has opposite 25 sides in parallel alignment with outer sides of

said section A. After said inner marginal lines of the opening A' extend upwardly a given distance they are overturned at each side and then turned downwardly to compose convex curve a², which extends within the 30 opening A' in direction toward upper marginal end of bar C. The section B has outward margins b, which continue from curves c' in approaching diagonal lines terminating in base b'. Said section B has an inner open- 35 ing B', the upper part being in a right line, and either side of said right line being the margin of the bar C. Said opening extends in parallel alignment with outer margins b and terminates with concaves b², between which 40 is a central convexed edge b³.

What I claim, and desire to secure by Letters Patent of the United States of America, is—

The design for a blank for a garment-fas- 45 tening hook as herein shown and described.

JACOB WHEATFIELD.
